(57) **CLAIM**

The ornamental design for a vehicle floor mat, as shown and described.

DESCRIPTION

FIG. 1 is a perspective view of a vehicle floor mat, showing my new design;

FIG. 2 is front view thereof; and,

FIG. 3 is an enlarged perspective view thereof.

The broken line showing of environment is for illustrative purposes only and forms no part of the claimed design.

1 Claim, 3 Drawing Sheets

FIG. 1

FIG. 2

FIG. 3
